UNITED STATES PATENT OFFICE.

WALTER WILKINSON, OF JERSEY CITY, NEW JERSEY, ASSIGNOR TO AIR REDUCTION COMPANY, INC., A CORPORATION OF NEW YORK.

COMPRESSION OF GASES.

Application filed March 5, 1920. Serial No. 363,621.

To all whom it may concern:

Be it known that I, WALTER WILKINSON, a citizen of the United States, residing at Jersey City, in the county of Hudson, State 5 of New Jersey, have invented certain new and useful Improvements in the Compression of Gases; and I do hereby declare the following to be a full, clear, and exact description of the invention, such as will enable others skilled in the art to which it ap-

10 pertains to make and use the same.

This invention relates to the compression of gas for storage in containers or "bottles" under pressure and particularly to a device 15 permitting compression of gases in water lubricated compressors and the delivery of the gas in a comparatively dry condition to the container.

Water lubricated compressors are com- 20 monly employed for compressing gases, such as oxygen which cannot be safely allowed to contact with oil when compressed. As a result, frequent complaint is heard that the containers are partly filled with water which, 25 of course, decreases the oxygen capacity beside causing trouble in apparatus such as regulating valves and oxy-acetylene blow-pipes wherein the gas is utilized.

The difficulty experienced results from the 30 fact that normally the compressor discharges directly to the filling line, and during the filling the pressure fluctuates from substantially atmospheric up to 2500 pounds per square inch as the pressure rises in the gas 35 containers. At low pressures, the saturated gas carries a large proportion of water vapor from the compressor and as the pressure rises in the container, the capacity of the gas to retain the moisture diminishes so that 40 water is deposited in the container.

When, however, the compressed gas is prevented from escaping from the compressor until the full pressure is developed and if this pressure is maintained, the gas being 45 released and fed to the filling line only when the predetermined pressure is exceeded, the difficulty referred to is substantially overcome. The only moisture which can be carried from the compressor is that absorbed

by a saturated gas at the maximum pressure, and at 2500 pounds per square inch, this moisture is negligible so far as the commercial utilization of the gas is concerned. The object, therefore, of the present invention is to provide a simple and dependable 55 method and means whereby the pressure may be held constant at the compressor while it varies in the filling line.

Further objects and advantages of the invention will be apparent as it is better understood by reference to the following specification and to the accompanying drawing, in which—

Fig. 1 is a diagrammatic view of an arrangement capable of fulfilling the condition; and

Fig. 2 is a detail in section of the valve.

The desired result is accomplished by the provision of a pressure controlling valve between the compressor and the filling line 70 which opens to permit the passage of gas to the filling line only when the pressure on the compressor side exceeds the predetermined maximum. Such a valve may be spring pressed and of suitable form and is 75 preferably balanced to prevent the varying pressure on the filling line side from affecting its operation. The details of the valve may vary and no attempt is made herein to illustrate more than the general form and principle of the valve together with its application, it being my intention to claim as my invention the means whereby the beneficial result described is developed.

Referring to Fig. 1 of the drawing, 5 indicates a water lubricated compressor which may be of any type or construction and may provide for compression in one or more stages. The compressor is provided with an intake 6 and an outlet 7, the latter communicating with a filling line 8 to which the containers or "bottles" 9 are connected.

Between the outlet 7 and the filling line 8, a valve casing 10 is arranged, the casing being provided, for example, with flanges 11 to facilitate connections. As illustrated in Fig. 2, the valve casing 10 is provided with a water trap 10' and a seat 12 between the

high pressure passage 13 and the variable pressure passage 14. A valve 15 is adapted to engage the seat under the influence of a spring 16 resting on the valve and bearing 5 against a screw 17 adjustably mounted in the casing 10. The pressure at which the valve is lifted from its seat may be varied at will by adjusting the screw.

Since the pressure in the passage 14 changes it would obviously affect the operation of the valve 15, unless prevented. To overcome the effect of the varying pressure, the valve 15 is provided with a stem 18 extending through a stuffing box 19 and carrying a piston 20 having an area equivalent to that of the face of the valve 15 which is exposed to the pressure in the passage 14. The piston 20 is disposed in a cylinder 21 and the space 22 within the cylinder and beneath the piston communicates through a pipe 23 with the passage 14. Thus the pressure in the space 22 is always equal to that in the passage 14, and the valve 15 will open at the predetermined pressure regardless of the pressure in the filling line. The space 24 above the piston is preferably connected to the intake of the compressor to return any gas leaking past the piston, but it must be borne in mind that the pressure 25 on the upper face of the piston must remain constant, unless pistons of different sizes are provided to ensure a balanced valve under the changed condition.

The mode of operation of the invention 35 should be readily understood. The spring 16, being adjusted to apply the desired pressure to the valve 15, the compressor is started and builds up the pressure until it overcomes the tension of the spring and lifts the 40 valve. Gas then flows into the filling line, but only so long as the pressure is maintained on the compressor side. If the pressure drops for any reason, the valve closes until the pressure again builds up in the 45 compressor. Thus the gas escapes from the compressor where it contacts with water only at a pressure which precludes the conveyance of any considerable quantity of water as vapor therefrom, and when the gas passes 50 the valve and its pressure decreases, it is no longer in contact with water which might be taken up at the lower pressure. The gas enters the containers therefor, in a substantially dry condition, a result which is 55 highly desirable and overcomes an objectionable feature of compressed gas as heretofore known.

Various changes may obviously be made 60 in the structural details as well as in the mode of applying the invention without departing from the spirit thereof.

I claim:

1. A method of compressing gases which comprises subjecting the gas to compression 65 in contact with water and limiting the

amount of water absorbed by the gas by maintaining a predetermined and maximum pressure at the outlet from the compressor and permitting the escape of gas to a region of variable pressure only when the predetermined pressure at the outlet is exceeded. 70

2. In an apparatus for compressing and storing gases, the combination of a water-lubricated compressor, a variable pressure filling line communicating therewith and means between said compressor and filling line to maintain a predetermined pressure in the former and to permit gas to escape to the latter only when said pressure is exceeded. 75

3. In an apparatus for compressing and storing gases, the combination of a water lubricated compressor, a variable pressure filling line communicating therewith and a spring pressed valve disposed between said compressor and filling line to prevent escape of gas to the latter only when a predetermined pressure is exceeded in the former. 80

4. In an apparatus for compressing and storing gases, the combination of a compressor, a filling line communicating therewith, a spring pressed valve disposed between said compressor and filling line to prevent escape of gas to the latter only when a predetermined pressure is exceeded in the former and means for balancing the pressure exerted by the gas on the filling line side of said valve. 90

5. In an apparatus for compressing and storing gases, the combination of a water lubricated compressor, a filling line communicating therewith and means for controlling the passage of gas to the filling line including a casing having high and variable pressure passages, a valve seat between the passages and a spring pressed valve adapted to engage the seat. 100

6. In an apparatus for compressing and storing gases, the combination of a water lubricated compressor, a filling line communicating therewith and means for controlling the passage of gas to the filling line including a casing having high and variable pressure passages, a valve seat between the passages, a spring pressed valve adapted to engage the seat, a cylinder, a piston in the cylinder and connected to the valve, and means connecting the cylinder to the variable pressure passage. 110

7. In an apparatus of the character described, a controlling device comprising a casing having high and variable pressure passages, a valve seat between the passages, a valve adapted to engage the seat, a spring engaging said valve, means for adjusting the tension of said spring and means for balancing the pressure of the gas in the variable pressure passage. 120

8. In an apparatus of the character described, a controlling device comprising a 125

casing having high and variable pressure passages, a valve seat between the passages, a valve adapted to engage the seat, a spring engaging said valve, means for adjusting the tension of said spring and means for balancing the pressure of the gas in the variable pressure passage including a cylinder, a piston in the cylinder and connected to the valve and communicating means between the cylinder and the variable pressure passage.

In testimony whereof I affix my signature.

WALTER WILKINSON.
